UNITED STATES PATENT OFFICE.

EMIL HENRY HABICK, OF EUCLID, MINNESOTA.

MOWER ATTACHMENT FOR CARS.

1,099,296.

Specification of Letters Patent.

Patented June 9, 1914.

Application filed March 1, 1912. Serial No. 680,996.

To all whom it may concern:

Be it known that I, EMIL H. HABICK, a citizen of the United States, residing at Euclid, in the county of Polk and State of Minnesota, have invented certain new and useful Improvements in Mower Attachments for Cars, of which the following is a specification.

This invention has relation to mower attachments especially adapted to be applied to hand cars and which is operated by an engine mounted upon the car. By providing a car with such an attachment the car may be passed along the track of the railway and the cutting apparatus of the attachment will operate upon grass at the side of the same as the car moves.

Means is provided for raising and lowering the cutting apparatus and the adjustment of the apparatus as indicated may be accomplished while the same is in operation or at rest.

For a full understanding of the invention reference is to be had to the following description and accompanying drawings, in which:

Figure 1 is an end elevation of a car with the attachment applied thereto; Fig. 2 is a top plan view of the same with parts broken away; Fig. 3 is a detail perspective view of winding drums used in connection with the attachment.

Corresponding and like parts are referred to in the following description and indicated in all the views of the accompanying drawings by the same reference characters.

As illustrated in the accompanying drawings an engine 1, preferably of the hydrocarbon type, is mounted upon a hand car 2. The car is of any usual pattern and any means may be provided for propelling the same along a track.

Bearings 3 are mounted upon the platform of the car 2 adjacent one edge thereof, and a shaft 4 is journaled in the said bearings 3. A pulley 5 is fixed to one end of the shaft 4 and a pulley 6 is mounted upon the shaft of the engine 1. A belt 7 is trained around the pulleys 5 and 6 and when the engine is in operation transmits rotary movement from the engine shaft to the shaft 4.

Brackets 8 are attached to the side edge 55 of the platform of the car. A straight arm 9 is pivoted to the foremost bracket 8 and

is adapted to swing vertically. An arm 10 is pivoted to the rear bracket 8 and is adapted to swing vertically. The arm 10 is provided with angularly disposed end portions and the outer end of the arm 10 is secured to the outer end portion of the arm 9. The inner portions of the arms 9 and 10 are parallel with relation to each other.

Bearings 11 are mounted upon the parallel portions of the arms 9 and 10 and a shaft 12 is journaled in the bearings 11. A sprocket wheel 13 of relatively small diameter is fixed to the shaft 12 and a sprocket wheel 14 of relatively large diameter is fixed to the shaft 4. A sprocket chain 15 is trained around the sprocket wheels 13 and 14 and is adapted to transmit rotary movement from the shaft 4 to the shaft 12. A disk 16 is fixed to the forward end of the shaft 12 at a point in advance of the arm 9 and is provided with an eccentrically positioned wrist pin 17. A bracket 18 is fixed to the outer end portion of the arm 9 and an inner shoe 19 is pivoted to the outer portion of the arm 9 and the bracket 18. A cutter bar 20 is fixed at its inner end to the shoe 19 and carries at its outer end a shoe 21. Guard fingers 22 are mounted at the forward edge of the cutter bar 20, and a knife bar 23 is mounted for reciprocatory movement along the forward edge of the cutter bar 20 and through the rear portions of the guard fingers in the usual manner. A pitman 24 is pivotally connected at its inner end to the wrist pin 17 and is pivotally connected at its outer end with the inner end portion of the knife bar 23. Therefore it will be seen that as the shaft 12 rotates, the pin 17 will reciprocate the pitman 24 which in turn reciprocates the knife bar 23.

A lifting arm 25 is mounted upon the platform of the car 2 in the vicinity of the forward end thereof and at the side edge thereof. The said arm is upwardly and outwardly inclined with relation to the platform of the car. A standard 26 is mounted upon the platform of the car 2 in the vicinity of the edge thereof opposite that edge at which the arm 25 is mounted. The standard 26 carries winding drums 27 and 28. Any suitable means may be provided for rotating the drums 27 and 28 and for holding the same against rotation.

Pulleys 29 and 30 are mounted at the outer end portion of the arm 25. A cable

31 is arranged to wind upon the drum 27 and is trained over the pulley 29. The outer end portion of the cable 31 is connected with the shoe 19. A cable 32 is arranged to wind 5 upon the drum 28 and is trained over the pulley 30. The outer end of the cable 32 is connected with the shoe 21. Therefore it will be seen that as the cable 32 is wound upon the drum 28 the outer shoe 21 will be 10 raised and the shoe 19 will turn upon its pivotal connection with the arm 9 and the bracket 18. Therefore the cutting apparatus may be inclined at a desired angle with relation to a horizontal and this adjustment 15 may be accomplished while the apparatus is in operation or at rest. By winding the cable 31 upon the drum 27 the shoe 19 will be raised and the arms 9 and 10 will swing upon their pivotal connections with the 20 brackets 8. Therefore the inner portion of the cutting apparatus may be raised while the said apparatus is in operation or at rest. By winding both cables 31 and 32 upon the drums 27 and 28 the entire cutting apparatus 25 may be raised without changing the disposition of the cutting apparatus with relation to a horizontal. This adjustment may also be accomplished while the apparatus is working or at rest.

30 Therefore it will be seen that a simple and an effective mower attachment is provided for a car and that the parts are susceptible of adjustment and movement to enable the apparatus to operate at the side of a track

irrespective of the inclination of the adjacent 31 banks, and also the cutting apparatus may be moved to clear obstructions at the side of the track as the car moves along the same.

Having thus described the invention, what is claimed as new is:

40 An apparatus of the character described including a wheeled support, a hanger arm pivotally connected to the support at one side edge thereof, an arm member rigidly secured to the support and extending upwardly and outwardly beyond that edge thereof to which the hanger arm is connected, pulley wheels journaled at the upper terminal of the second-mentioned arm member, a cutting apparatus pivotally connected 45 to the outer terminal of the hanger arm, operating means for the cutting apparatus, a pair of cables one of which is secured to the inner end of the cutting apparatus and the other of which is secured to the outer 50 end of the cutting apparatus, said cables being directed through the pulleys of the second-mentioned arm member, and independent operating means mounted on the support for each of the cables, whereby the inner 55 and outer ends of the cutting apparatus may be independently raised or lowered.

56 In testimony whereof I affix my signature in presence of two witnesses.

EMIL HENORY HABICK. [L. S.]
